EDWARD G. BUDD, OF PHILADELPHIA, PENNSYLVANIA, ASSIGNOR TO
HALE-KILBURN METAL COMPANY, OF PHILADELPHIA, PENNSYLVANIA, A CORPORATION OF PENNSYLVANIA.

CAR-SEAT.

No. 823,256.

Specification of Letters Patent.

Patented June 12, 1906.

Application filed April 26, 1905. Serial No. 257,538.

To all whom it may concern:

Be it known that J. EDWARD G. BUDD, a citizen of the United States, residing at Philadelphia, in the county of Philadelphia and 5 State of Pennsylvania, have invented a certain new and useful Improvement in Car- Seats, (Case A,) of which the following is a specification.

The invention relates particularly to an 10 improved frame for car-seats and the like, and has for its object to produce a strong and durable device, constructed, preferably, of pressed steel, which may be economically manufactured and easily assembled.

15 A further object is to provide a structure which while meeting the requirements of practical use shall be capable of expression in graceful form, adding to the ornamental appearance of the seat as a whole.

20 In carrying out the invention I employ as part of the seat-frame a suitable support, on one or both sides of which is mounted a seat end including an arm-rest and made, preferably, in the form of two pressed-steel sections 25 having coacting lips, whereby such sections may be permanently secured together by rivets or other suitable means. The arm-rest, of wood or metal and of any desired configuration, may be mounted upon and attached to said sections in any suitable manner. Within the space between such sections I mount struts coacting with the internal faces of such sections and preventing collapse thereof. Extending through said sections and through said struts are bolts, headed on either side of said sections and preventing expansion thereof. The construction as thus briefly disclosed possesses great strength and rigidity and in addition by the adoption 30 of paneling, graceful lines, &c., may be made highly ornamental in appearance.

The invention is illustrated in the accompanying drawings, in which—

Figure 1 is an end view of a car-seat provided with my invention. Fig. 2 is a section on the line 2 2, Fig. 1, with the arm-rest removed; and Fig. 3 is a section on the line 3 3, Fig. 1.

Referring to the drawings, in which similar letters denote corresponding parts, A designates the supporting member of the seat-frame, here shown in the form of a pedestal and carrying the seat end B. Of the lat-

ter there may be but one, the mechanism of the seat at the other end being supported by the side wall or a suitable frame-plate carried thereby. Within the frame is mounted a suitable seat-cushion C and back D, the latter being preferably of the reversible "walk-over" type and so coacting with the seat-cushion as to transmit movement thereto upon reversal from one facing direction to the other.

Turning now to the seat end B more particularly concerned in the present invention, this is here shown as formed in two substantially similar sections b b', although they may of course be varied within wide limits. Each section is preferably stamped or pressed from a single integral sheet of steel, a single operation not only determining its configuration, but also paneling the same, as shown, for instance, in the drawings, where the main body portion is provided with parallel ribs or beads b'', and the edges of such body portion, as well as of the upwardly-extending arms b''' are bowed or curved outwardly upon symmetrical lines, giving the appearance of column-like supports for the arm-rest E. The extreme (abutting) edges of each of the sections b b' are provided with coacting beads or flanges, extending inwardly, as shown, or outwardly. In practice the extreme edge of one section will be given a slight flare in order that the plates may be joined under pressure and held by their coaction with each other during the further assembling of the several parts. The overlapping edges are permanently and rigidly connected by means of rivets b''. As thus constituted the seat end, with the arm-rest E in place thereon, is practically complete in appearance. To give it additional strength, as well as to permit the use of relatively thin sheets of steel without introducing the undesirable element of weakness, I provide the seat end, on each side of the center thereof, with a strut F, here shown as formed of two parallel metallic bars of substantial thickness and coextensive in width with the space between the adjacent inner faces of the sections b b', so as to abut against the same and prevent collapse thereof. Said bars are secured together by any suitable means—as, for instance, by rivets f—and have angular oppositely-extending feet f', closing the recess between the sec-

tions b b' , through which such struts are inserted. At suitable intervals throughout their length the members of each of said struts are separated sufficiently to permit the passage between the same of bolts f^2 , which pass also through suitable orifices in the sections b b' , each of said bolts having a head at one end (preferably the outer end) and a screw-thread and nut at the other. Upon placing 10 the bolts f^2 in position and turning the nuts home thereon the sections b b' are clamped firmly against the edges of the struts F , whereby not only is undue expansion prevented, but the seat end as a whole rigidly 15 united and capable of resisting any strain to which it may be subjected in practice.

The exact shape or configuration of the seat end or those of the struts F is of course immaterial, and much latitude may be observed in this regard; also, if desired, the arm-rest may be formed integral with the sections b b' or one of them, or, if separate, such sections may be provided with shoulders b^6 , either integral therewith or separate therefrom to afford greater bearing for such separate arm-rest. These and many other modifications may readily be made without departing from the spirit or sacrificing the advantages of the invention.

30 Having now described my invention, what I claim as new therein, and desire to secure by Letters Patent, is as follows:

1. In a car-seat, a metallic seat end comprising two pressed sheet-metal plates having flanges at their lateral edges bent to close the lateral edges of the seat end and means for securing said plates together, a pedestal on which said seat end is mounted, a seat and a movable back supported by said seat 35 end and an arm-rest secured on the upper edge of the seat end above the seat and in a plane parallel with the seat, substantially as set forth:

2. In a car-seat, a metallic seat end comprising two sheet-metal plates, a spacer between them and means securing the plates together, said plates having flanges at the lateral edges bent to close the lateral edges of the seat end, and a flange at the top, and an 40 arm-rest secured on said flange at the top of the seat end in a plane parallel with the seat, substantially as set forth.

3. In a car-seat, a metallic seat end comprising two sheet-metal plates, a spacer between them and means securing the plates together, said plates having flanges at the lateral edges bent to close the lateral edges of the seat end and inwardly-turned flanges on the upper edges of the plates, a seat and a 45 movable back supported by said seat end, and an arm-rest detachably secured on said inwardly-turned flanges above the top of said seat, substantially as set forth.

4. In a car-seat, a metallic seat end comprising two sheet-metal plates, a spacer be-

tween them and means securing the plates together, said plates being pressed to form columns at the lateral edges and flanges at said edges bent to close the lateral edges of the seat end, a seat and a movable back supported by said seat end, and an arm-rest secured on the upper edge of said seat end above the top of said seat and overlying the ends of said columns, substantially as set forth. 75

5. In a car-seat, a metallic seat end comprising two sheet-metal plates, a spacer between them, means securing the plates together, flanges at the lateral edges of said plates bent to close the lateral edges of the seat end, flanges at the top of the plates and means for securing the last-named flanges together, and an arm-rest secured upon said last-named flanges, substantially as set forth. 80

6. In a car-seat, a metallic seat end comprising two sheet-metal plates, a spacer between them, means securing the plates together, flanges at the lateral edges of said plates bent to close the lateral edges of the seat end, flanges at the top of the plates and 90 means for securing the last-named flanges together, and an arm-rest detachably secured upon said last-named flanges, substantially as set forth. 95

7. In a car-seat, a metallic seat end comprising two sheet-metal plates, a strut between them, a bolt passing through the plates and strut and securing them together, flanges closing the lateral edges of the plates, flanges at the upper edges of the plates and 100 means securing said last-mentioned flanges together, and an arm-rest secured on said last-mentioned flanges, substantially as set forth.

8. In a car-seat, a metallic seat end comprising two sheet-metal plates, a strut between them, a bolt passing through the plates and strut and securing them together, flanges closing the lateral edges of the plates, flanges at the upper edges of the plates and means 110 securing said last-named flanges together, and an arm-rest detachably secured on said last-mentioned flanges, substantially as set forth.

9. In a seat, the combination with a frame, of a seat end comprising two substantially parallel plates, means for securing said plates together at one edge thereof, an arm-rest secured upon said edge, a two-part strut between said plates and abutting against the 120 internal faces thereof, and means for securing said plates and strut together, substantially as set forth. 115

10. In a seat, the combination with a frame, of a seat end formed in sections, a two-part strut between such sections and abutting against the internal faces thereof, and means for securing said sections and strut together, substantially as set forth. 125

11. In a seat, the combination with a 130

frame, of a seat end formed in sections, a two-part strut between such sections, said parts being secured together but having passages between such parts, and bolts passing through said sections and through the passages in said strut, substantially as set forth.

12. In a car-seat, a metallic seat end comprising two sheet-metal plates, a perforated spacer between them having integral portions bent at an angle to the body portion thereof and means extending through the perforation in said spacer for securing the plates together, said plates having flanges closing the lateral edges of the seat end and a flange at the top and an arm-rest secured upon said flange at the top of the seat end, substantially as set forth.

13. In a car-seat, a metallic seat end com-

prising two pressed sheet-metal plates having flanges at their lateral edges bent to close the lateral edges of the seat end and having overlapping portions, rivets coacting with said portions to secure the plates together, a pedestal on which said seat end is mounted, a seat and a movable back supported by said seat end and an arm-rest secured on the upper edge of the seat end above the seat and in a plane parallel with the seat, substantially as set forth.

This specification signed and witnessed this 18th day of April, 1905.
